2,299,324

PROTECTOR FOR BREECHES

John W. Henderson, Madison, Pa.

Application April 5, 1941, Serial No. 387,078

1 Claim. (Cl. 2—228)

This invention relates to a protector for breeches and has for an object to provide flared legs for the breeches provided at their lower ends with elastic bands whereby to adapt the flared portions to be easily and quickly folded upwardly out of the way preparatory to fastening cuffs extending from the knee portions of the breeches to a point below the flared portions and putting on the boots.

A further object is to provide breeches with flared portions having elastic bands on the lower ends adapted to be placed over the upper ends of the leg portions of the boots, the elastic bands causing the flared portions to hug the boot legs snugly and prevent access of dust, rain and snow to the wearer's feet and legs.

A further object is to provide breeches of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part 30 of this specification:

Figure 1 is a front elevation of breeches constructed in accordance with the invention.

Figure 2 is a detail longitudinal sectional view of the breeches leg showing the flared portion extending downwardly upon and hugging the upper portion of a boot.

Figure 3 is a detail side elevation of the breeches leg with a portion broken away to expose the lacing of the cuff.

Figure 4 is a cross sectional view showing the knee portion, cuff and flare portion of the breeches leg, drawn to large scale.

Referring now to the drawing in which like characters of reference designate similar parts in the various views, 10 designates breeches, and in accordance with the invention, the legs of the breeches extend approximately six inches below the knees, those portions 11 extending below the 50

knees being flared and provided at the lower ends with elastic bands 12 secured in respective hems 13 formed at the bottom of the flared portions.

Cuffs 14, closed by laces 15, are attached at 5 their upper ends to the inner surface of the knee portions, that is upper ends, of the flared portions 11 by respective lines of stitching 16. The cuffs project below the flared extended leg portions 11 and are adapted to fit the leg tightly and hold the extended leg portions 11 from accidental movement off the tops of the boots 17.

The elastic bands 12 adapt the flared leg portions 11 to be easily and quickly folded upwardly above the knees out of the way, preparatory to 15 lacing or buttoning the cuffs 14, and putting on the boots. The elastic bands also adapt the flared leg portions 11 to be readily placed over the upper ends of the leg portions of the boots, the bands causing the flared portions 11 to hug the boot leg 20 snugly and prevent access of snow, rain and dirt to the feet of the wearer.

From the above description it is thought that the construction and operation of the invention will be fully understood without further explanation.

What is claimed is:

Breeches having legs extending a short distance below the knees of the breeches, those portions extending below the knees being flared and provided at the lower ends with elastic bands secured in respective hems formed at the bottom of the flared portions, laced cuffs attached at their upper ends to the legs above the upper ends of the flared portions by respective lines of stitching, said cuffs projecting below the flared extended leg portions and being adapted to fit the wearer's leg tightly, said cuffs being adapted to be inserted in the upper ends of knee length boots, said elastic bands adapting the flared leg portions to be easily folded upwardly above the knees of the wearer out of the way preparatory to the lacing of the cuffs and putting on the boots, said elastic bands also adapting the flared leg portions to be readily placed over the upper ends 35 of the knee length boots and subsequently causing the flared portions to hug the boot legs snugly and prevent access of snow, rain and dirt to the tops of the boots.

JOHN W. HENDERSON.
